US00D701890S

(12) **United States Design Patent**
Wilson et al.

(10) **Patent No.:** US D701,890 S
(45) **Date of Patent:** ** Apr. 1, 2014

(54) **MULTIPLE SPINNER CAROUSEL FOR DRESSING A GRINDING WHEEL**

(71) Applicant: **1339513 Ontario Ltd.**, Harrow (CA)

(72) Inventors: **Murray David Wilson**, Harrow (CA);
Steven David Wilson, Harrow (CA);
Omer Leon Hageniers, Windsor (CA)

(73) Assignee: **1339513 Ontario Ltd.**, Ontario (CA)

(***) Term: **14 Years**

(21) Appl. No.: **29/453,378**

(22) Filed: **Apr. 29, 2013**

Related U.S. Application Data

(63) Continuation of application No. 29/428,491, filed on Jul. 31, 2012, now Pat. No. Des. 681,077, which is a continuation of application No. 29/388,322, filed on Mar. 28, 2011, now Pat. No. Des. 665,830.

(57) **CLAIM**

The ornamental design for a multiple spinner carousel for dressing a grinding wheel, as shown and described.

DESCRIPTION

FIG. 1 is a perspective view of a multiple spinner carousel in accordance with the present teachings.

FIG. 2 is an opposite view of FIG. 1.

FIG. 3 is a partial exploded assembly view showing rotatable spinners spaced from the multiple spinner carousel of FIG. 1.

FIG. 4 is an opposite view of FIG. 1.

FIG. 5 is another perspective view of the multiple spinner carousel of FIG. 1.

FIG. 6 is a further perspective view of the multiple spinner carousel of FIG. 1.

FIG. 7 is a top view of the multiple spinner carousel of FIG. 1.

FIG. 8 is a bottom view of the multiple spinner carousel of FIG. 1.

FIG. 9 is a front view of the multiple spinner carousel of FIG. 1.

FIG. 10 is a rear view of the multiple spinner carousel of FIG. 1.

FIG. 11 is a side view of the multiple spinner carousel of FIG. 1.

FIG. 12 is an opposite view of FIG. 1; and,

FIG. 13 is a perspective view of the multiple spinner carousel of FIG. 1 attached to a grinding machine adjacent a grinding wheel in accordance with the present teachings.

The broken lines in the drawings depict unclaimed environmental subject matter.

1 Claim, 8 Drawing Sheets
